UNITED STATES PATENT OFFICE.

WILLIAM CLINE, OF LANCASTER, PENNSYLVANIA.

SWINGING FAN.

Application filed August 6, 1927. Serial No. 211,147.

This invention relates to fans and more particularly to a swinging fan of the multiple type adapted to be suspended from a ceiling or other overhead support and have oscillatory motion imparted to it so that air in a room will be kept in motion.

One object of the invention is to so mount the air agitators that they will be disposed in a substantially vertical position and cause the air to be thoroughly agitated when they are oscillated and caused to have a sweeping motion.

Another object of the invention is to counterbalance the weight of the upper and lower portions of the air agitators so that they will be evenly balanced and permitted to be swung very easily.

Another object of the invention is to provide improved actuating means for the air agitators including a substantially endless cable and means for imparting motion thereto first in one direction and then in a reverse direction.

Another object of the invention is to provide an improved guide for the actuating cable including a pulley rotatably mounted and slidable vertically so that there will be no danger of the cable moving out of proper engagement with the pulley.

Another object of the invention is to firmly connect the shank of a fan blade with a cross-head forming part of the agitator and to so mount the blade that it may be vertically adjusted and thereby disposed in proper spaced relation to the ceiling of a room.

The invention is illustrated in the accompanying drawing, wherein

Figure 1 is a view showing the improved fan in side elevation;

Fig. 2 is a view showing the operating means for the fan in end elevation;

Fig. 3 is an enlarged view of one of the air agitators showing the same in elevation;

Fig. 4 is a view showing the agitator partially in side elevation and partially in section, and

Fig. 5 is a fragmentary sectional view taken on the line 5—5 of Fig. 4.

The improved fan is to be suspended from a ceiling or other overhead support and in-

cludes end hangers 1 and 2 and intermediate hangers 3 which carry air agitators, indicated in general by the numeral 4. Each of the hangers 3 is provided with depending transversely spaced arms 5 having bearings 6 at 55 their lower ends to receive a shaft 7 about which is disposed a tubular crosshead 8. The crosshead 8 carries anti-friction rollers 9 so that it may turn freely upon the shaft 7 and is formed with an upwardly extending 60 internally threaded socket 10 and a depending neck 11. The fan blade 12 which is preferably formed of strong sheet metal has been shown semi-circular in shape and is carried by a U-shaped shank 13 formed from a metal 65 rod bent intermediate its length and having the joined lower ends of its arms 14 disposed about a fastener 15 between the blade 12 and a washer 16. By this arrangement the blade may be slid longitudinally upon the 70 shank to dispose it the desired distance from the ceiling of a room and it will be frictionally held in a set position. The upper ends of the arms 14 are disposed against a flat surface of the neck 11 and are firmly held thereto 75 by a cross strip or plate 17 and securing bolt 18. By this arrangement the shank will be firmly secured to the crosshead but may be easily detached therefrom when necessary.

The handle 19 of the fan consists of a rod 80 or pipe of a suitable length which has its lower end portion threaded and screwed into the socket 10 and its upper end portion also threaded and carrying a nut 20 constituting a support for a suitable number of lead or other 85 metal disks 21. Since the nut or support 20 is threaded upon the handle it may be adjusted thereon in order to accommodate the desired number of weights or disks 21 without danger of them slipping off the handle. 90 It will be obvious that, if desired, a retainer nut may be threaded upon the handle above the weights and firmly hold them in place.

The hanger 1 is somewhat similar to the hangers 3 but is provided with only one arm, 95 the lower end of which is bent to form a side extension 22 to engage and support the lower end of a circular rod or pin 23. This rod carries a roller 24 which is of a concaved formation and is rotatably and slidably mounted 100

upon the rod. The other end hanger 2 is formed with depending side arms 25 having bearings 26 at their lower ends and in these bearings is journaled a crank shaft 27, the 5 cranks 28 and 29 of which extend in opposite directions and carry loosely mounted sleeves 30. Between the arms 25 the crank shaft carries a rigidly secured pulley 31 about which passes a belt 32 trained about a pulley 33 upon the shaft 34. The shaft 34 is journaled in bearings carried by the support 35 and it will be readily seen that when the shaft 34 is rotated through the medium of a belt 36 leading from a motor or other source of power and trained about the pulley 37 rotary motion will be imparted to the crank shaft 27. The crank arm 29 of the crank shaft is connected with the handle of the adjacent agitator by a short rope or cable 38 and a long 10 rope or cable 39 is secured to the crank arm 28 and after being trained about the guide pulley 24 is secured to the handle of the agitator next to the hanger 1. Rods or cables 40 extend between and are secured to the handles of the agitators in a tightened condition, and it will be readily seen that when the crank 15 shaft is rotated its arms will alternately exert a pulling action upon the cables 38 and 39. Therefore, the agitators will be swung and oscillated first towards the hanger 1 and then toward the hanger 2 and as they swing the blades 12 will cause the air in a room to be thoroughly agitated and prevented from becoming stagnant. It will, of course, be understood that additional agitators and hangers 20 for the same may be provided if the fan is to be installed in a very large room or only one employed if the fan is used in a small room. As the crank shaft turns, the cable will receive a certain amount of vertical swinging movement due to the movement of the crank arm 28 but since the guide pulley is slidable upon its rod 23 there will be no danger of this cable slipping out of proper engagement with the guide pulley. If it is found that the blades are not properly spaced from the ceiling, they may be easily adjusted upon their shanks and if it is found that the fans do not swing properly weights may be added to or removed from the handles until 25 the upper and lower portions of the fans are counter-balanced.

Having thus described the invention, I claim:

1. A fan system comprising a rotatably 30 mounted crank shaft having crank arms extending in opposite directions, a guide pulley rotatably mounted and slidable vertically, hangers between said guide pulley and crank shaft, fans having vertically disposed handles pivotally connected with said hangers and blades at their lower ends, cables connecting the upper end portions of said handles, a cable connected with the upper end portion of the handles of a fan adjacent the pulley and trained about said pulley and se-

cured to one crank arm of the crank shaft, and a cable connecting the other crank arm of the crank shaft with the upper end portion of the handle of a fan adjacent the crank shaft. 70

2. A fan system comprising end hangers and an intermediate hanger between the end hangers, a horizontal crank shaft rotatably supported by one end hanger, a pulley rotatably supported by the other end hanger and slidable vertically thereon, an agitator having a vertically disposed handle pivoted intermediate its length to the intermediate hanger and a blade at the lower end of the handle, a flexible member connecting the upper end portion of said handle with a crank arm of said crank shaft, and a second flexible member connected with the upper end portion of said handle and trained about said pulley and connected with another crank arm of the 85 crank shaft.

3. A fan system comprising end hangers, one having depending bearing arms and the other a vertically extending rod, a pulley rotatably mounted upon said rod and slidable 90 vertically thereon, a crank shaft rotatably supported by said bearing arms and having crank arms extending in opposite directions, an agitator between said hangers having a vertically disposed handle pivotally mounted 95 between its upper and lower ends and a blade carried by the lower end of the handle, flexible means connecting said handle with one crank arm, and flexible means connected with the other crank arm and trained about 100 said pulley and connected with the handle.

4. A fan system comprising end hangers, one having depending bearing arms and the other a vertically extending rod, a pulley rotatably and slidably mounted upon said rod, 105 a crank shaft rotatably supported by said bearing arms and having crank arms extending in opposite directions, an intermediate hanger between the end hangers and having spaced depending bearing arms, an agitator 110 including a cross-head rockably mounted between the bearing arms of the intermediate hanger and having an upstanding socket and a depending arm intermediate its length, a handle carried by said socket, a shank having its upper end removably secured against the depending arm, a blade carried by said shank and adjustable longitudinally upon the shank between the crosshead and the lower end of the shank, a cable connecting 115 said handle with one crank arm and secured to said handle, and a second cable connected with the other crank arm and trained about the slidable pulley and secured to said handle. 125

5. A fan system comprising a hanger having spaced depending bearing arms, an agitator including a crosshead rockably mounted between the bearing arms of said hanger and having an upstanding socket and a depending 130

arm intermediate its length, a handle carried by said socket, a U-shaped shank having the upper ends of its arms secured against the depending arm of said crosshead, a blade 5 fitted against said shank and having a fastener passing between the arms thereof to connect the blade with the shank and permit

adjustment of the blade longitudinally thereon, and actuating means connected with said handle and adapted to impart swinging 10 movement to the fan.

In testimony whereof I affix my signature.

WILLIAM CLINE. [L. S.]
